UNITED STATES PATENT OFFICE

FREDERICK GEORGE GARRETT, OF SOUTHALL, ENGLAND

TENT

Application filed December 28, 1928. Serial No. 328,916.

This invention relates to tents, an object thereof being to provide a tent which can be erected without the aid of either a central pole or guy ropes. Another object is to provide a tent framework suitable for such a tent as aforesaid, which framework is adapted to be collapsed into a small compass for storage or transport. Another object is to adapt the upper part of the said framework 10 to be expanded so as to increase the head room in the tent when erected. Other objects and advantages of the said invention will appear from the following detailed description of an exemplification thereof in conjunction with 15 the accompanying drawings wherein:—

Figure 1 is an elevation representing the framework of the tent expanded.

Figure 2 is an elevation representing the framework of the tent collapsed.

Figure 3 is a plan of a compound disc uniting the stay rods of the tent.

Figure 4 is an inverted plan showing the underside of the said compound disc.

A indicates the lower member of the disc, 25 which is secured by screws a' to the annular upper member B. This member B has a number of radial slots b' and a down-turned flange b^2 which latter is interrupted at intervals for the entry of a number of slides C. Each of these slides C has a T head D adapted to ride over the surface of the member B and overlap the edges of the radial slots b' . At the other end of each 30 slide C are a pair of lugs E and a hinge pin F. Set screws G having milled heads g' work through the member A and are adapted to engage the undersides of the slides C so as to hold the said slides in position when they have been adjusted with their lugs E close to the flange b^2 . A number of stay rods, struts, or legs H are arranged around the disc, each 35 terminating in a loop h' entering between the lugs E and embracing the hinge pin F, on which latter they can turn freely. These stay rods are telescopic, that is, each comprises four or other number of concentric members H, h^2 , h^3 and h^4 , adapted to slide longitudinally on or in each other, three of which members are provided with spring catches of a 40 kind well known in telescopic tripods for

supporting cameras, whereby the full extension of the stay rods is maintained when the tent framework is erected. At the lower end of each stay rod is secured an inclined tube J, through which a headed or tapered tent peg 55 can be passed and driven obliquely into the ground by means of a mallet or the like, the slope of all these tubes J being towards the centre of the tent framework.

A hole K in the centre of the disc A may 60 serve for the attachment of a hook (not shown) on which garments or other articles may be hung.

When erecting the tent, the slides C are drawn out, the stay rods H swung to incline 65 outwardly to the extent necessary to delimit the base of the tent when the telescopic portions of the said stay rods are fully drawn out, suitable pegs are driven through the tubes J into the ground, and a suitable canvas or other cover placed over the framework 70 thus set up. The said cover may be fastened if desired to any convenient parts of the framework.

When it is desired to pack up the tent, the 75 cover is removed and rolled or folded, the pegs withdrawn from the tubes, the telescopic portions of the stay rods collapsed, the slides C pushed into the slots b' and secured by turning the set screws G, and all the 80 stay rods brought together into an approximately cylindrical form.

While I have above described a constructional form of this invention whereby the objects of the invention can be attained, it 85 will be obvious that changes in detail can be made therein without departing from the principles of the invention, which is to be understood as including any such variations as may fall within the scope of the following claims.

What I claim and desire to secure by Letters Patent of the United States is:—

1. In a tent framework, a disc and a plurality of stay rods hinged adjacent to the periphery of said disc, said stay rods each terminating at its free end in an obliquely arranged tube for the reception of a peg to secure it to the ground. 95

2. In a tent framework, a disc and a plu- 100

rality of stay rods hinged adjacent to the periphery of said disc, said stay rods being of telescopic construction and each terminating at its free end in an obliquely arranged tube for the reception of a peg to secure it to the ground.

3. In a tent framework, a disc, a plurality of slides radially movable in relation to said disc, and a plurality of stay rods each pivotally connected with one of said slides.

4. In a tent framework, a disc comprising a lower member and an annular flanged upper member, a plurality of slides penetrating the flange of said upper member and radially movable in relation to said disc, and a plurality of stay rods each pivotally connected with the outer end of one of said slides.

5. In a tent framework, a disc comprising a lower member and a radially slotted upper member, a plurality of slides each provided with means for engaging the edges of the radial slots in said upper member to guide said slides in radial movements in either direction, and a plurality of stay rods each pivotally connected with the outer end of one of said slides.

6. In a tent framework, a disc, a plurality of slides adapted to be adjusted radially in relation to said disc, means for securing said slides in adjusted position, and a plurality of stay rods each pivotally connected with the outer end of one of said slides.

7. In a tent framework, a disc comprising upper and lower members spaced apart, a plurality of slides adapted to be adjusted radially in the space between said members, means for guiding said slides in their radial movements, means for securing said slides in their adjusted positions, and a plurality of stay rods each pivotally connected with the outer end of one of said slides.

FREDERICK GEORGE GARRETT.
